UNITED STATES PATENT OFFICE.

LAWRENCE RICHARDSON, OF LOUISVILLE, KENTUCKY.

SIX-WHEEL-TRUCK BOLSTER.

Application filed August 6, 1923. Serial No. 655,828.

To all whom it may concern:

Be it known that I, LAWRENCE RICHARDSON, a citizen of the United States, residing at Louisville, in the county of Jefferson and State of Kentucky, have invented certain new and useful Improvements in Six-Wheel-Truck Bolsters, of which the following is a specification.

This invention relates to six-wheel truck bolsters.

One object of the invention is to provide a six-wheel truck bolster which is relatively flexible for equalizing the distribution of the loads and at the same time has a minimum number of parts which are connected in a manner to minimize the extent to which the truck can get out of square.

Another object is to provide an interlocking bolster for six-wheel trucks adapted to meet the various requirements under service conditions.

These and other objects are accomplished by means of the arrangement disclosed on the accompanying sheet of drawings, in which—

Figure 1 is a fragmentary top plan view of a railway car truck embodying my invention;

Figure 2 is a side elevation of the same car truck;

Figure 3 is a top plan view of my improved bolster;

Figure 4 is a front elevation of the same; and

Figure 5 is a side elevation of said bolster.

The various novel features of the invention will be apparent from the following description and drawings, and will be particularly pointed out in the appended claims.

Referring to the figures of the drawings, it will be noted that my invention is illustrated in connection with a six-wheel truck having side frames 10 (only one of which is shown), having end journal box openings 11 for the reception of end journal boxes 12, and openings 13 through which transverse bolster members 14 extend. The ends of the transverse bolster members 14 rest upon springs 9 seated on equalizing levers 15 pivotally connected at 16 to the associated side frame 10, one of said equalizing levers 15 having pedestal jaws for the reception of an intermediate journal box 17 and the other equalizing lever cooperating with its associated equalizing lever for

transmitting loads to the intermediate journal box. The loads are transmitted from the transverse bolster members 14 to the equalizing levers 15, such loads being distributed directly to the intermediate journal box through the equalizing levers 15 and indirectly to the end journal boxes 12 from the equalizing levers 15 through the side frame 10.

This invention has to do particularly with the bolster which, in this instance, is a three piece bolster or a three unit bolster. One unit includes one of the transverse bolster members 14 and a longitudinal bolster member 18, which, preferably, are integrally formed. The second unit includes the other transverse bolster member 14 and another longitudinal bolster member 18, preferably integrally formed. The third bolster unit comprises the main bolster member 19 which is separate from the other bolster members and is supported by the longitudinal bolster members 18, preferably by having its outer ends extend through openings 20 in longitudinal bolster members 18 and resting upon the floor of said openings. The main bolster member 19 carries the center plate and transmits the loads to the longitudinal bolster members 18 which, in turn, transmit the loads to transverse bolster members 14 from which the loads are distributed through the equalizing levers to the various journal boxes, as above described.

Each longitudinal bolster member is integrally formed with its associated transverse bolster member 14 at a point on said transverse bolster member about one-quarter of its length from one end thereof. The free end of each longitudinal bolster member 18 has jaws 21 which fit over reduced portions 22 of the other transverse bolster member 14 in a manner to form a flexible connection between such bolster members for giving the required flexure to the bolster construction for equalizing the distribution of the loads. At the same time the releasable or sliding joint connections between the free end of each longitudinal bolster member and the opposite transverse bolster member is made sufficiently rigid to minimize the extent to which the truck can get out of square. In this construction the line of flexure is a straight line connecting the points at which the free ends of the longitudinal bolster members 18 are loosely joined with the opposite transverse bolster members 14. These

joints or points of contact are comparatively far apart and in view thereof any play in these joints will have but little effect on the amount the four legs or bolster members 14 and 18 can get out of square with respect to each other. This also reduces the rolling resistance of the truck as well as the wear of the wheel flanges. If desired, in order to simplify the foundry operation, the transverse bolster members 14 may be cast separately from their associated longitudinal bolster members 18 and then securely connected to form the two separate units, each unit consisting of one transverse bolster member 14 and a longitudinal bolster member 18. In each case, however, a longitudinal bolster member 18 will have a sliding joint connection with the opposite transverse bolster member for giving the required amount of flexure for load equalizing and at the same time minimize the extent to which the truck can get out of square.

The side bearings may be carried by either the main bolster 19 or by the interlocking bolster members, but preferably the side bearings are located on the main bolster 19 outside the longitudinally extending bolster members 18.

It is my intention to cover all modifications of the invention falling within the spirit and scope of the following claims.

I claim:

1. In a bolster for six-wheel trucks, the combination of a unitary transverse bolster member and longitudinal bolster member, and a second unitary transverse bolster member and longitudinal bolster member, said units being separate and interlocked for giving the required flexure for load equalizing and at the same time minimize the extent to which the truck can get out of square.

2. In a bolster for six-wheel trucks, the combination of a unitary transverse bolster member and longitudinal bolster member, and a second unitary transverse bolster member and longitudinal bolster member, said units being separate and interlocked for giving the required flexure for load equalizing and at the same time minimize the extent to which the truck can get out of square, and a main bolster member for transmitting loads to said bolster units.

3. In a bolster for six-wheel trucks, the combination of two integrally formed bolster units, each bolster unit including a transverse bolster member and a longitudi-

dinal bolster member, said units being flexibly connected for load equalizing and at the same time connected in a manner minimizing the extent to which the truck can get out of square. 60

4. In a bolster for six-wheel trucks, the combination of two separate units, each unit including a transverse bolster member integrally formed with a longitudinal bolster member, each of said units having a jaw for releasably slidably fitting a portion of the other unit for giving the required flexure for load equalizing and at the same time 70 minimizing the extent to which the truck can get out of square.

5. In a bolster for six-wheel trucks, the combination of two separate units, each unit including a transverse bolster member integral- 75 ly formed with a longitudinal bolster member, each of said units having a jaw for releasably slidably fitting a portion of the other unit for giving the required flexure for load equalizing and at the same time minimizing 80 the extent to which the truck can get out of square, and a main bolster member connecting the longitudinal bolster members.

6. A bolster for six-wheel trucks comprising three units, two of said units each comprising a transverse bolster member integrally formed with a longitudinal bolster member, each longitudinal bolster member being flexibly connected to the opposite transverse bolster member to form a line of 90 flexure diagonally across the bolster for equalizing the distribution of the load and at the same time minimize the extent to which the truck can get out of square, the third bolster unit connecting the longitudi- 95 nal bolster members.

7. In a bolster for six-wheel trucks, the combination of a unitary bolster member having a transversely extending portion and a longitudinally extending portion, a second 100 unitary bolster member having a transversely extending bolster portion and a longitudinally extending bolster portion, said units being separate and interlocked for giving the required flexure for load equalizing, said longitudinally extending bolster portions having seats, and a main bolster member carried by said longitudinally extending portions and having bearings outside of said seats. 105

Signed at Chicago, Illinois, this 3rd day of August, 1923.

LAWRENCE RICHARDSON.
